UNITED STATES PATENT OFFICE.

JOSEPH GREENBURG, OF BOSTON, MASSACHUSETTS.

WINDOW.

1,385,539.

Specification of Letters Patent. Patented July 26, 1921.

Application filed January 20, 1920. Serial No. 352,869.

To all whom it may concern:

Be it known that I, JOSEPH GREENBURG, a citizen of the United States, residing at Boston, county of Suffolk, State of Massachusetts, have invented an Improvement in Windows, of which the following description, in connection with the accompanying drawing, is a specification, like characters on the drawing representing like parts.

10 This invention relates to windows and has for its object to provide a novel window construction having window sashes which can be raised and lowered in the usual manner to open and close the window and which 15 can also be swung inwardly into the room to facilitate the cleansing of the outside surface of the glass.

In order to give an understanding of my invention, I have illustrated in the drawings a selected embodiment thereof which will now be described, after which the novel features will be pointed out in the appended claims.

Figure 1 shows a window embodying my invention taken from the inside of the room;

Fig. 2 is an enlarged fragmentary sectional view on the line 2—2, Fig. 1;

Fig. 3 is a view on the line 3—3, Fig. 2;

Fig. 4 is a sectional view showing the 30 manner in which the window sashes are swung inwardly;

Fig. 5 is a fragmentary view of one of the lower corners of the window frame and the lower sash showing the sash partly elevated;

Fig. 6 is a view of one corner of one of the sashes;

Fig. 7 is a view on the line 7—7, Fig. 4.

Fig. 8 is a view showing how my invention may be used for ventilating purposes.

1 indicates a window frame, 2 a lower sash operating therein and 3 an upper sash. The window frame may be of any suitable construction either metal or wood, although 45 I have herein shown for illustrative purposes a metal frame. This window frame is formed on each side with a guiding shoulder 4 against which the lower sash 2 rests and by which it is guided in its vertical movement. Said frame is also provided on each side with another guiding shoulder or way 5 against which the upper sash 3 rests and by which it is guided. The window frame is further provided on each side with two 55 grooves 6 and 7 in which are received trunnions 8 and 9 carried by the sashes 2 and 3,

respectively. The trunnions 8 and 9 are situated at the lower edges of the sashes and these trunnions not only assist in guiding the sashes in their vertical movement, but 60 also form the trunnions about which the sashes may be swung into the room. The trunnions further provide means for attaching the sash cords 10 to the sashes. These guiding grooves 6 and 7 extend the 65 full length of the window frame and as the sashes are raised or lowered the guiding trunnions 8 and 9 on the sashes move up and down in the grooves. Each sash is also provided with guiding projections situated 70 above the trunnions and which operate in the grooves 6 and 7, said projections coöperating with the trunnions to hold the sashes in vertical position against the guiding shoulders 4 and 5. The projections on 75 the lower sash 2 are indicated at 11 and they are preferably of smaller diameter than the trunnions and are situated so that when the window sash is in operative position they bear against the front face of the guiding 80 groove 6. The corresponding projections on the upper sash 3 are indicated at 12, there being one such projection on each side of the sash, and these projections also bear against the front face of the guiding 85 groove 7.

Means are provided for releasably retaining the projections 11 of the lower sash in the grooves 6, the construction being such that when the projections are withdrawn 90 from the grooves the window may be swung inwardly about the trunnions 8, as shown by the full line position Fig. 4. When the window is thus swung into its horizontal position it is situated within the room of the 95 building and the outer face of the glass 13 can be readily cleaned by a person standing in the room.

For thus permitting the sash to be swung from its operative vertical position against 100 the shoulder 4 into its horizontal position, I provide the front wall of each groove 6 with an opening 14 which is adapted to be closed by a slide 15 that operates within the window frames and is provided with a knob 105 16 by which it can be moved vertically. This knob 16 extends through a slot 17 in the front of the window frame. So long as each slide 15 is in a position to close its slot 14, the window sash will be held in its vertical operative position against the shoulder 4 and may be raised and lowered as an ordinary

nary window sash. If it is desired to swing the window sash into its horizontal position into the room, as shown in Fig. 4, the slides 15 will be raised thereby to open the slots 14 and the window sash 2 will be moved into a position to bring the projections 11 in line with said slots 14. When in this position the window sash may be swung forwardly about the trunnions, during which operation the projections 11 pass through the slots 14. A reversal of these operations will bring the window sash back to its normal vertical position again against the shoulders 4.

15 A somewhat similar construction permits the upper sash 3 to be swung into a horizontal position within the room. The upper sash 3 is made somewhat narrower than the lower sash 2, as shown in Fig. 3, and the 20 grooves 7 which guide the upper sash are directly back of the shoulders 4 against which the lower sash rests. The front wall of each groove 7 is provided with an opening or slot 18 through which the projections 25 12 may pass. These slots 18 are preferably arranged at the lower portion of the frame and slightly above the slots 14. As stated above, the upper sash 3 has a less width than the lower sash 2 and the projections 12 come 30 within the portions 19 of the window frame against which the edges of the sash 2 bear. In order to swing the upper sash inwardly, it is necessary first to throw the lower sash into its horizontal position shown in full 35 lines Fig. 4, after which the upper sash may be lowered to bring its projections 12 into line with the slots 18, after which said sash can be swung inwardly, as shown by dotted lines Fig. 4.

40 The lower sash is shown as having an apron 20 depending from its lower edge which fits against the raised portion or ledge 21 of the window sill when the lower sash is in its operative position and closed.

45 I have provided herein means to limit the swinging movement of the lower sash 2. This means herein illustrated is in the form of a stop lug or projection 22 secured to the under side of the lower sash at the end in 50 line with the apron 20 and a slot 23 formed in the shoulder 4. When the sash 2 is swung into horizontal position, Fig. 4, the projection 22 will swing into the slot 23 and by its engagement with the upper edge of the slot 55 will act as a stop to limit the horizontal swinging movement of the sash 2 and thus hold said sash in such horizontal position while it is being cleaned. Said projection also acts as a stop to prevent the sash from 60 moving upwardly when it is in its horizontal position. It will be remembered that the sash cords are connected to the trunnions 8, and when the window is thrown into its horizontal position the tendency of the sash 65 weights would be to raise the bottom of the

window up since the entire weight of the window does not come on the sash cords. The engagement of the projection 22 against the top of the slot 23 will prevent this upward movement of the window sash.

A similar stop may be provided for the upper sash which would consist of a projection 24 adapted to enter a slot formed in the shoulder 5.

70 My construction is also valuable for ventilation purposes. If it is desired to provide ventilation, the lower sash may be swung inwardly slightly, as shown in Fig. 8, thus opening a sufficient space between the top of the lower sash and the bottom of the upper sash to provide the requisite ventilation. For holding the lower sash in its ventilating position, I have shown a chain or connection 41 secured to the window frame and adapted to engage a hook 42 on the window sash.

75 While I have illustrated herein a selected embodiment of my invention, I do not wish to be limited to the constructional features shown.

80 I claim:

1. In a window, the combination with a window frame having a guiding groove in each side, of a sash having trunnions operating in said grooves and also having projections normally received in the grooves 95 which coöperate with the trunnions to hold the sash in operative position, said window frame having slots extending entirely through one wall of each groove to permit the projections to pass therethrough whereby the window sash may be swung into horizontal position, and a stop projection extending from the bottom of the sash to coöperate with one wall of one groove to limit the swinging movement of the sash. 100

105 2. In a window, the combination with a window frame having a guiding groove in each side, of a sash having trunnions operating in said grooves and also having projections normally received in the grooves 110 which coöperate with the trunnions in holding the sash in operative position, said window frame having slots through one wall of each groove to permit the projections to be removed from the grooves and the window sash to be swung into horizontal position, and slides for closing said slots. 115

3. In a window, the combination with a window frame having a sash-guiding shoulder on each side, of a sash resting against said shoulder, means for holding said sash in vertical position against said shoulder while permitting it to swing inwardly, one of said shoulders having a slot, and a stop projection extending from the sash and adapted to enter said slot when the sash swings inwardly, the wall of the slot co-operating with the projection to limit the swinging movement. 120

4. In a window, the combination with a 125

window frame having a sash-guiding shoulder and a guiding groove in each side, of a sash arranged to rest against said shoulders and having trunnions operating in said 5 grooves about which the sash may be swung away from the shoulders, releasable means for holding the sash in its operative position against the shoulder, said shoulders having slots therein, and projections ex-

tending from the sash and adapted to enter 10 said slots as the sash swings about the trunnions, the walls of said slots coöoperating with the projections to limit the swinging movement.

In testimony whereof I have signed my 15 name to this specification.

JOSEPH GREENBURG.
